(57) **CLAIM**

The ornamental design for an end assembly for electric and communication cables, as shown and described.

DESCRIPTION

FIG. 1 is a front perspective view of the end assembly for electric and communication cables, showing our new design; FIG. 2 is a rear perspective view of the end assembly for electric and communication cables; FIG. 3 is a front view of the end assembly for electric and communication cables; FIG. 4 is a rear view of the end assembly for electric and communication cables; FIG. 5 is a first side view of the end assembly for electric and communication cables; FIG. 6 is a second side view of the end assembly for electric and communication cables; FIG. 7 is a bottom view of the end assembly for electric and communication cables; and, FIG. 8 is a top view of the end assembly for electric and communication cables.
